TWO-BAND SIGNAL RECEIVING SYSTEM

Wendell L. Carlson, Haddonfield, N. J., assignor
to Radio Corporation of America, a corporation
of Delaware

Application August 6, 1941, Serial No. 405,696

3 Claims. (Cl. 250—20)

This invention relates to a two-band signal receiving system which is responsive to signals in an ultra-high frequency band such as the signal receiving band between 42 and 50 mc. and the low frequency or broadcast frequency band between 530 and 1700 kc.

It is an object of this invention to provide an improved and simplified input circuit for a super-heterodyne receiving system responsive to an ultra-high frequency and a low frequency signal receiving band and to provide variable tuning throughout each of said bands with a minimum number of tuning elements and with a single tuning control means.

In the construction of radio receiving systems, the tuning element may comprise a simple two or three-unit variable capacitor, the maximum number being three units for maintaining the overall size of the apparatus within limits prescribed by modern design and to maintain a low production cost.

Accordingly, it is a further object of this invention to provide an improved and simplified input circuit for signal reception in an ultra-high frequency and a low frequency signal receiving band which is variably tunable throughout each of said bands with a variable tuning capacitor having three tuning units.

It is a further object of this invention to provide an improved tuning system for a super-heterodyne receiver responsive to two differing frequency bands which may be operated in the higher frequency or ultra-high frequency band with minimum cross modulation of received signals.

The invention will, however, be further understood from the following description, when considered in connection with the accompanying drawing, and its scope is pointed out in the appended claims.

Referring to the drawing, the figure is a schematic circuit diagram of a radio signal receiving system embodying the invention, in which 5 and 6 represent a dipole antenna connected through a transmission line 7 with the terminals 8 of a balanced primary winding 9 of an ultra high frequency input coupling transformer 10. This transformer is provided with a balanced secondary 11, the terminals 12 and 13 of which are connected with the signal input or control grids 14 and 15, respectively, of a balanced detector comprising suitable electric discharge tubes 16 and 17, which may be triodes as indicated.

The grids are provided with the usual coupling capacitors 18, and grid resistors 19, which may be

connected with any suitable source of biasing potential as indicated. The cathodes 20 and 21 of the balanced detector are connected in parallel to ground 23 through a lead 22 and two series-connected cathode coupling windings 24 and 25, the latter having a shunt capacitor 26.

The anodes 28 and 29 of the balanced detector are connected to the terminals 30 and 31 of a balanced primary winding 32 of an intermediate frequency transformer 33, the secondary of which is indicated at 34. The latter is tuned by a shunt capacitor 35 and a suitable magnetic tuning core 36 to a high intermediate frequency for the reception of signals in the ultra high frequency band for which the receiver is designed.

The detector anodes 28 and 29 are connected in parallel relation to the primary 40 of a low frequency intermediate frequency transformer 41 through a connection with the midtap 42 of the balanced primary 32 and to a positive source of anode potential indicated by the lead 43. The alternating current path is completed to ground from the lead 43 through a bypass capacitor 44. The primary 40 is suitably tuned to the low intermediate frequency by a shunt capacitor indicated at 45.

The secondary 46 of the low intermediate frequency transformer 41 is tuned to the lower intermediate frequency by a shunt capacitor indicated at 47 and a suitable magnetic tuning core indicated at 48. Both primaries 32 and 40 may likewise be tuned by means of suitable magnetic tuning cores indicated at 49 and 50.

The two secondaries 34 and 46 for the high and low intermediate frequency channels are serially connected with the signal input grid 51 of an intermediate frequency amplifier 52, the high frequency secondary 34 being connected more adjacent to the grid 51 or at the high potential side of the circuit while the secondary 46 is connected more adjacent to the bias supply connection indicated at 53.

The output anode circuit 54 of the amplifier stage 52 is connected serially in circuit with two tuned primary windings 55 and 56 of a two-channel intermediate frequency amplifier which may be of any suitable type, although preferably constructed in accordance with Carlson Patent 2,167,605 which provides two amplifying channels with a single series of cascade-connected tubes arranged between the coupling transformers in a manner similar to that shown for the tube 52. The output transformers comprise tuned secondary windings 57 and 58 coupled to the primary windings 55 and 56, respectively,

and having a common output circuit indicated at 59.

The antenna input primary 9 is provided with a center tap 60 which is connected to ground 61 through a low frequency primary winding 62 of a low frequency input coupling transformer 63, the secondary of which is indicated at 64. The latter is connected between ground 65 and a center tap 66 on the balanced secondary 11 of the ultra high frequency input circuit and is variably tunable through a predetermined low frequency range by a variable shunt capacitor indicated at 67.

The cathode coupling windings 24 and 26 are coupled respectively to the oscillator circuits 70 and 71, respectively, which are variably tunable in unison with the circuit 64-67 by suitable means such as variable capacitors 72 and 73 connected in shunt with the tuning inductances 74 and 75 which are coupled respectively with the windings 24 and 25. The variable tuning means 67, 72 and 73 may be connected as indicated by the dotted line 76 for unitary control whereby the system may be tuned by single tuning means, which in this case may be the usual three-unit gang variable capacitor.

In the present example, the oscillators comprise oscillator tubes 80 and 81 coupled to the circuits 70 and 71 for generating oscillations in a high and a low frequency range for which the receiving system is designed, and are controlled selectively for operation in the two ranges by means of switches 82 and 83 in the cathode circuits 84. The present arrangement is such that the switch 82 is open when the switch 83 is closed, and vice versa, to place one or the other of the oscillators in operation as a simple band changing means.

The oscillators may be any suitable type, and in the present example are of the feedback type having a control grid 85 connected with the tuned oscillator circuit and an anode 86 coupled to said tuned circuits through suitable coupling windings 87.

In the system shown, the dipole antenna 5-6 is connected with the balanced primary winding 9 which, in turn, is coupled through the balanced and broadly tuned secondary 11, with the balanced detector tubes 16 and 17 which, in turn, transmit signals through the balanced primary winding 32 to the intermediate frequency amplifier 52.

Oscillator voltage is impressed on the balanced detector tubes 16 and 17 through the cathode coupling winding 24 with the cathodes in parallel. This is the receiving circuit for ultra high frequency signals, such as signals in the 42 to 50 mc. band. For this frequency band, the low frequency winding 62 does not carry radio frequency currents and winding 64 is bypassed by capacity 67. On the intermediate frequency or output side of this circuit, the primary winding 40 has no R. F. or I. F. potentials impressed on it and the secondary winding 46 is bypassed by capacity 47.

For the broadcast or low frequency signal band, the antenna 5-6 operates as a T-type antenna supplying signals to the low frequency primary 62 through the high frequency primary 9 which offers substantially no impedance to signals in the low frequency or broadcast band. Signals from the primary 62 are applied to the tunable secondary 64 and to the detector grids 14 and 15 in parallel through the secondary 11 which offer substantially no impedance to signals in the

low frequency band. The detector tubes 16 and 17 operate to apply intermediate frequency signals to the low intermediate frequency primary 40 in parallel through the primary 32, and the intermediate frequency signals are applied to the amplifier 51 from the secondary 46, the high frequency primary and secondary offering substantially no impedance to signals in the low intermediate frequency band.

The oscillator applies voltage to the cathode circuit through the coupling winding 25, and as in the ultra high frequency band, the cathodes receive the oscillator voltage in parallel. The only switching required to change from one signal band to the other is to energize the oscillators 80 and 81 selectively by suitable switching means such as that shown in the present example.

By the simple circuit arrangement shown, the oscillator voltage is applied to the same cathode circuit and to the balanced detector cathodes in parallel for both the ultra high frequency and low frequency signal receiving bands. The push-pull or balanced ultra high frequency input circuit and output circuit for the detectors is effective to reduce cross-modulation of signals received through the ultra high frequency pass band circuits, while the tuning is accomplished by merely the oscillator tuning in the circuit 70. Furthermore, with this arrangement, a simple three-gang variable capacitor or its equivalent is all that is required for tuning the system variably through two differing frequency bands.

I claim as my invention:

1. A two-band signal receiving system comprising, in combination, a balanced detector comprising a pair of detector tubes having input and output electrodes and a common cathode connection therefor, a high frequency input circuit and a high intermediate frequency output circuit connected in balanced relation respectively to the input and output electrodes of said tubes, each of said circuits having a center tap, an oscillator coupled through said cathode connection to said tubes in parallel, a low frequency input circuit connected through the center tap on said first-named input circuit with the input electrodes of said tubes in parallel, a low intermediate frequency output circuit connected through the center tap on said first-named intermediate frequency output circuit with the output electrodes of said tubes in parallel, and a second oscillator coupled through said cathode connection to said tubes in parallel.

2. A two-band signal receiving system comprising, in combination, a detector having a balanced grid circuit, a high frequency input transformer having a broadly tuned secondary winding connected in balanced relation to said grid circuit, a high intermediate frequency balanced output circuit for said detector, an output transformer having a primary winding connected in balanced relation to said output circuit, a common cathode circuit for said detector, a high frequency oscillator coupled to said cathode circuit, a low frequency input circuit connected with said detector through the center connection on said secondary winding, a low intermediate frequency output circuit connected with said detector through the center connection on said primary winding, a low frequency oscillator coupled to said cathode circuit, and means for selectively energizing said oscillators.

3. A two-band signal receiving system comprising, in combination, a balanced detector having a pair of signal grids, a pair of cathodes and

a pair of anodes, a high frequency input circuit connected in balanced relation to said grids, a high intermediate frequency output circuit connected in balanced relation to said anodes, an oscillator coupled to said cathodes in parallel, a low frequency input circuit connected through said first-named circuit with said grids in parallel, a low intermediate frequency output circuit connected through said first-named intermediate

frequency output circuit with said anodes in parallel, a second oscillator coupled to said cathodes in parallel, a signal supply circuit coupled to said input circuits, means for selectively energizing said oscillators, and means for jointly tuning said low frequency input circuit and said oscillators in unison.

WENDELL L. CARLSON.
